EARTH MOVING EQUIPMENT

Frank W. McLarty, Dallas, Tex.

Application March 13, 1957, Serial No. 646,190

16 Claims. (Cl. 172—67)

This invention relates to new and useful improvements in earth moving implements.

One object of the invention is to provide an improved earth moving implement which is so constructed as to be particularly adapted for use in building terraces to control and prevent soil erosion.

Another object of the invention is to provide an improved earth moving implement having an earth cutting disc and a coacting rotor for receiving and throwing the earth cut by the disc, the rotor and disc being adjustable relative to each other and to the ground for varying the action and coaction thereof in accordance with earth and terrain conditions as well as the type of terrace desired.

A particular object of the invention is to provide an improved earth moving implement, of the character described, wherein the disc and rotor are mounted for adjustment about an upright axis so as to be readily reversible for directing and throwing earth laterally in either direction.

An important object of the invention is to provide an improved implement, of the character described, wherein the rotor includes a revolving member having a plurality of radial elements, adjacent the disc for receiving earth directly from said disc and casting the earth laterally without undue lifting thereof whereby increased earth moving efficiency is obtained.

Still another object of the invention is to provide an improved implement, of the character described, which includes novel means for mounting the rotor whereby the same may undergo substantially universal adjustment relative to the disc.

A further object of the invention is to provide an improved earth moving implement having a frame adapted to be pivotally mounted on a tractor and carrying a grader blade at one end for counterbalancing plow means at the other end of the frame whereby the blade and plow means are available for building terraces, the weight of the tractor and the traction of its rear wheels are increased and lifting of the plow means from engagement with the earth is facilitated.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a perspective view of an earth moving implement, constructed in accordance with the invention,

Fig. 2 is a perspective view of the front end of the implement, showing the grader blade raised,

Fig. 3 is a rear elevational view of the implement mounted on a tractor,

Fig. 4 is a rear elevational view of the mounted implement, the tractor being shown in broken lines,

2

Fig. 5 is an enlarged, transverse, vertical, sectional view, showing the mounting of the grader blade,

Fig. 6 is a plan view of the mounted implement, the tractor being shown in broken lines,

Fig. 7 is an enlarged, detailed view, partly in section, showing the mounting of the rotor supporting means,

Fig. 8 is an enlarged, transverse, vertical, sectional view, showing the transmission mounting,

Fig. 9 is a fragmentary, underside plan view, showing the pivotal mounting of the plow assembly, and

Fig. 10 is an enlarged, transverse, vertical, sectional view of the reversing mechanism.

In the drawings, the numeral 10 designates the frame of an earth moving implement which includes a pair of angular, longitudinal bars or frame members 11 having substantially horizontal, parallel front and rear portions 12 and 13 connected by inclined intermediate portions 14. The front frame portions 12 are offset downwardly relative to the rear frame portions 13 which are fastened together by a cross bar or member 15. As shown by the numeral 16, the extremities of the rear frame portions diverge for supporting an arcuate or semi-circular, horizontal, guide bar or frame member 17 extending transversely of the frame 10 with its ends directed forwardly in substantially parallel relation to the bars 11. A rearwardly-directed, V-shaped bracket or frame member 18, having longitudinal legs 19, is secured to the ends of the front frame portions by its arms being bolted or otherwise rigidly fastened thereto as shown by the numeral 20. The rear frame portions 13 are adapted to be pivotally attached to the rear ends of a substantially U-shaped, rearwardly-directed sub-frame 21 by suitable bolts 22.

As shown by the numeral 23, the front end portion of the sub-frame is offset downwardly in parallel relation to the major portion thereof and is adapted to be rigidly connected by pairs of spaced bolts 24 to the underside of the rear axle housing 25 of a tractor (Figs. 3 and 6). It is noted that the sub-frame 21 extends rearwardly from the axle housing, preferably in a horizontal plane and inwardly of the frame 10 and that said frame 10 extends forwardly and rearwardly of said sub-frame and the axle housing 25. A transmission 26 is pivotally supported at its rear portion by an angular, transverse bracket or member 27 bolted to inwardly-directed lugs 28 between the rear ends of the sub-frame and has a forwardly-projecting shaft 29 carrying a double-groove pulley 30. A pair of endless belts 31 connect the pulley 30 to a complementary, overlying pulley 32 mounted on the power take-off shaft 33 of the tractor. Since the transmission 26 is supported only at its rear portion, it is manifest that its forward portion, shaft and pulley are urged downwardly by its weight to tighten and maintain the belts 31 in engagement with the pulleys.

A plow assembly 34 is pivotally mounted on the rear end portion of the frame 10 and includes a horizontal, substantially A-shaped frame 35 formed of angular, diverging bars or members 36 having their outer, rear ends 60 connected by a transverse bar or member 37. The A-frame extends rearwardly in underlying relation to the frame and its semi-circular guide bar 17 and has its apex pivotally suspended from the medial portion of the cross bar 15 by an upright bolt or pin 38 (Fig. 9) so as to be capable of undergoing substantially horizontal swinging movement transversely of said frame. A pair of angle plates or hangers 39 depend from the juncture of the bars 36 and 37 for supporting a horizontal, mounting bar 40 at their lower ends. Rotatably suspended from the bar 40, by means of a suitable spindle bracket 41, is a plow 42 of the disc type. The end bar 37 is angular in cross-section and has its upper flange directed forwardly and

overlying the guide bar 17 which has a plurality of openings 43 for receiving a bolt 44 carried by said end bar to support the A-frame 35 in adjusted positions about the upright axis of the pivot pin or bolt 38. Manifestly, the plow assembly 34 may be swung transversely relative to the frame 10 upon removal of the bolt 44 in order to vary the angular relation of the disc 42 to the tractor and to move said disc from one side of the implement to the other. A linkage 45 is connected to and extends forwardly from one of the bars 36 whereby the plow assembly may be swung by mechanical or hydraulic means (not shown) from the tractor and held in adjusted positions.

A rotor assembly 46 is provided for coacting with the plow assembly and its disc and includes a drive shaft 47 journaled in a tubular housing 48 extending rearwardly from the transmission 27 and connected thereto by a universal joint 49. It is noted that the universal joint 49 is disposed in substantial alignment with the ends of the bracket 27 and their supporting lugs 28 so that their respective axes intersect. The rear end of the shaft housing 49 is connected by a right-angle gear case 50 to the upper end of a substantially upright shaft housing 51 having a driven shaft 52 journaled therein and extending therethrough (Fig. 10). A bevelled pinion 53 is keyed on the rear end of the drive shaft 47 for meshing with a pair of complementary drive gears 54 and 55 journaled on the upper end of the driven shaft 52 in the gear case 50 whereby the drive gears rotate in opposite directions upon rotation of said drive shaft. The upper end of the driven shaft has splined connection with a slidable connecting element or sleeve 56 having external splines 57 for meshing with internal splines 58 and 59 formed on the drive gears 54 and 55, respectively.

For slidably actuating the sleeve 56, an upstanding rod 60 projects from its upper end through the top of the gear case and is pivotally attached to a lever 61 pivoted at 62 to an upright quadrant 63 mounted on said gear case. The quadrant 63 has a pair of notches 64 in its arcuate margin for receiving a transverse latch pin 65 removably engaged with the lever 61. As shown in Fig. 10, downward swinging of the lever raises the rod 60 and sleeve 56 to move the splines 57 into engagement with the splines 58 of the upper drive gear 54 and out of engagement with the splines 59 of the lower drive gear 55. Conversely, the splines 56 are disengaged from the upper drive gear splines and engaged with the lower drive gear splines upon lowering of the sleeve and its rod by upward swinging of the lever (Fig. 1). Since the sleeve is splined to the driven shaft, said shaft is rotated in one direction or the other depending upon which drive gear is connected to said sleeve.

A rotor element 66 is carried by the driven shaft 52 and includes a pair of circular plates or hubs 67 confined upon the lower projecting end of said shaft by a nut 68 and fastened together in spaced relation by suitable nuts and bolts 69. The spaced hubs 67 have a plurality of substantially radial fingers or tines 70 projecting therefrom and clamped therebetween by the bolts 69. Preferably, the tines are in the form of V-shaped members confined by the bolts as shown at 71 (Figs. 3 and 6). Although the tines 70 may be straight as shown in Fig. 1, preferably, said tines have their outer portions curved upwardly (Figs. 3 and 4) whereby the rotor element may be positioned in close proximity to the plow 42 and said tines may move past the rear portion of said plow without striking the uncut earth. Also, the curvature of the tines permits the same to move more quickly into contact with the cut earth. For supporting the rotor assembly, a bifurcated lever 72 extends longitudinally of and is pivotally connected to the drive shaft housing 48 and has a pair of angular arms 73 diverging outwardly from their inner ends. As shown by the numeral 74 in Fig. 7, the intermediate portions of the arms 73 extend in parallel relation to and on either side of a collar 75 concentrically surrounding the housing 48 and rotatably confined

thereon by a pair of retaining rings 76. A pair of diametric studs 77, having suitable nuts 78, project from the collar 75 for pivotally supporting the intermediate arm portions 74. The collar supports an upstanding ratchet quadrant 79 for coacting with a conventional releasable pawl mechanism 80 carried by the inner ends of the arms and forming a part of the lever 72 (Figs. 1 and 3) whereby said lever may be latched in adjusted position relative to the drive shaft housing. A support for the rotor assembly is provided by the outer diverging end portions of the lever arms overlying and bearing against the guide bar 17. Manifestly, the rotor assembly may be raised and lowered by swinging the lever relative to the housing 48 and its collar 75, and such movement of said assembly is permitted by the universal joint 49.

For supporting the rotor assembly in angularly-adjusted, transverse positions, a chain 81 is attached to the intermediate portion of the driven shaft housing 51 and is adapted to be engaged in a notch 82 formed in the outer extremity of each arm 73 which projects rearwardly of the guide bar. If desired, a linkage 83 may be connected to the housing 48 for swinging and holding the rotor assembly in adjusted positions relative to the implement frame and its plow assembly 34 by mechanical or hydraulic means (not shown) from the tractor. An upstanding stop bar or lug 84 is adjustably clamped on a bar member 36 of the A-frame 35 for engagement by the housing 48 to limit movement of the rotor assembly toward the plow assembly and determine the spacing between the disc 42 and rotor element 66.

Due to the mounting of the rotor assembly, it is manifest that said assembly may undergo substantially universal movement. Raising and lowering of the rotor element is accomplished by swinging the lever 72, while the chain 81 permits fastening of said element in tilted positions relative to the disc plow. The rotor element may be swung in a transverse arc about the axis of the universal joint 49 due to the support provided by the coaction of the guide bar 17 and lever. Since the plow assembly is readily adjustable from side to side of the implement frame, the relative positions of the rotor and plow assemblies may be reversed so that said plow assembly is mounted on the right-hand instead of the left-hand side to permit reverse or two-way operation. Of course it is necessary to reverse the direction of rotation of the shaft 52 by shifting the connecting sleeve 56. The other adjustments of the rotor element may be readily performed and, if desired, such adjustments may be relatively minute. In addition to the transverse adjustment of the plow assembly, the elevation of both assemblies may be readily varied in view of the pivotal mounting of the frame members 11 provided by the bolts 22. A linkage 85 from the tractor is adapted to be connected to lugs 86 carried by the legs 19 for pivoting the implement frame about the axis of the belts.

It is noted that the disc 42 is adapted to cut and direct earth laterally of the direction of travel to the rotor element 66 without undue lifting of the earth. Upon receiving the laterally-directed earth, the rotor element carries and throws said earth in a generally lateral direction. Although the rotor element may be tilted transversely of the implement frame to lift the earth, it is pointed out that there is no unnecessary lifting action and that the force generated by the revolving element is utilized primarily to impart lateral movement to said earth. Also, the earth may be lifted sufficiently, when the tines 70 are curved upwardly as shown in Figs. 3 and 4, whereby tilting further of the rotor element may be unnecessary. Of course, the rotor element may be tilted longitudinally of the frame in order to cast the earth at a forward or rearward angle relative to the disc. Since the rotor element is power-driven, it usually revolves at a greater speed than the disc so as to accelerate the lateral movement of the earth and pick up and remove the cut earth from said disc so as to prevent undue

accumulation. Due to the radial disposition of the tines 70, their outer portions are spaced apart a greater distance than their inner portions; and outward as well as downward movement of the earth is facilitated. As a result, the tines are substantially self-cleaning even at relatively slow speeds of rotation. Another advantage of the implement resides in the adjustability of the disc and rotor element in accordance with varying earth conditions and types of earth. As has been explained, the elevation of both the disc and rotor element may be changed readily; and said element may undergo substantially universal adjustment relative to said disc. Since the rotor element may be raised independently of the disc, said disc may be employed to cut an initial furrow or furrows prior to the earth throwing or terrace building operation.

Another feature of the invention resides in the provision of a grader blade 87 at the forward ends of the frame members 11 to counterbalance the plow and rotor assemblies. A pair of axially-aligned, spaced sleeves 88 are secured to the upper, rear surface of the grader blade by overlying angle bars 89 and extend longitudinally of said blade for receiving a cylindrical rod or pivot pin 90. Intermediate the sleeves 88, the pivot pin 90 is welded or otherwise secured to the forward side of an upright tubular bearing 91 having a rearwardly-extending, semi-circular plate 92 fastened to its upper end and reinforced by a gusset 93 (Figs. 5 and 6). A gudgeon bolt 94 projects upwardly through the plate 92 with its circular head 95 confined in the bearing 91 for pivotally suspending the blade 87 from a collar 96 at the apex of the V-shaped bracket 18. The bolt 94 is retained in position by a suitable nut 97 overlying the collar. A substantially arcuate plate 98 is secured within the bracket rearwardly of the collar 96 in overlying relation to the plate 92 and has an opening 99 for registering with one of a plurality of openings 100 formed in a concentric arc in the rear, arcuate edge portion of said plate 92. For holding the plate 98 in adjusted positions relative to the plate 92 and maintaining the grader blade in adjusted angular relation to the implement frame, a headed pin 101 is adapted to be received by the registering openings 99 and 100. The inclination or tilt of the blade 87 is controlled by set screws 102 carried by an angle bar 103 extending longitudinally of said blade and secured to the lower end of the bearing 91. A lever 104 is connected to one of the angle bars 89 for tilting the grader blade upwardly out of operating position and may be engaged beneath the bracket 18 as shown in Fig. 2.

It is noted that the grader blade is most useful in building terraces. Upon downward pivoting of the implement frame about the axis of the bolts 22, the plow and rotor assemblies are lifted and the blade is lowered into engagement with the ground. Although the blade may be employed primarily to smooth terraces by removing high spots and filling low spots, it is frequently necessary to move the earth longitudinally or lengthwise of a terrace, and this is best accomplished by a blade. If desired, the earth may be cut or loosened by the disc prior to the grading operation. In addition, the blade may be utilized to move relatively loose or loosened earth laterally to build small terraces or initiate larger terraces to be formed by the coaction of the disc and rotor element. Also, due to the pivotal mounting of the implement frame, the blade may be swung upwardly by the linkage 85 to lift the earth during the grading operation in order to deposit said earth at the desired location. Due to the mounting of the blade and plow on opposite ends of the frame, said plow is counterbalanced and is more readily disengaged from the earth. Also, the entire weight of the implement is supported at the rear wheels of the tractor so as to increase the traction thereof. Since the blade and plow are essential to earth moving or terracing operations, it is most ad-

vantageous, economical, and time and labor saving to provide the same in a single implement. Manifestly, the coutilization of the blade and plow is enhanced by mounting the same on a common frame, whereby their desired weight is utilized at all times, and whereby either is readily available at any time. You don't have to go back across the field or to the implement yard to get the proper implement, when it already is attached to the other end of the frame.

The foregoing description of the invention is explanatory thereof; and various changes in the size, shape, and materials, as well as in the details of the illustrated construction, may be made, within the scope of the appended claims, without departing from the spirit of the invention.

Be it noted that I have shown a means of building a power-driven rotor in conjunction with a slightly concave rolling disk plow as the most desirable embodiment of my invention. Be it further noted that I am the discoverer of a most unusual attribute of a rolling disc plow in conjunction with such a rotor as an earth moving mechanism, by way of contrast with previous mechanisms that have used rotors in conjunction with conventional earth loosening plows of the cut-and-lift mouldboard variety. Reference is here made to the fact that a rolling disk plow starts a gradual and increasing acceleration of all the dirt moved by it to the side from the time that the edge of the disk first cuts the soil. Previous rotary terracing machines have failed largely because they failed to accelerate all the soil gradually, even before coming in contact with the rotor, in order to obviate problems of abrasion etc. Having observed this attribute of the rolling disc plow, in addition to the well known facts that it would loosen even hard soil and turf, required no rolling coulter in order to handle surface trash, etc., I have demonstrated a means whereby a power-driven rotor is made to get under and come in contact with all the earth proceeding from the trailing lower quadrant of the disc in such manner that the acceleration of the soil, trash, rocks, etc. is continued to the side or to the rear by the whirling of the rotor with a minimum of abrasion thereto.

A portion of the above recited desirable feature of a rotor in conjunction with a rolling disc plow may be said to come from the fact that the soil will adhere to the disc slightly as a result of the cup of the disc and of pressure, regardless of moisture content of the soil, so that all the soil will be lifted slightly before flowing out onto the rotor, which can even turn freely below the stream of soil at first. This results in a minimum power requirement for operation of the mechanism for earth moving.

It is recognizable, however, that, if the "angle of attack" of the face of the disc relative to the direction of its furrow is decreased and the vertical angle also is decreased, a concave disc might be made to operate without turning, although more power would be required and abrasion of the rotor elements would be increased. Of course, if the disc did not turn, the upper part of the disc would not be necessary, although it might be the easiest way to manufacture such an earth-loosening and directing plow because of the strength imparted by the completion of the "cup." Although such construction does not appear practicable for any purpose at present, it is suggested merely as a possibility; and it may be noted that a variation of the axis of the rotor might be found desirable. But in any event the novel feature is the way in which an arc described by rotating teeth or tines would bisect the space between the uncut earth and an earth loosening, directing, and accelerating means substantially corresponding to the trailing lower quadrant of a rolling concave disc plow.

What I claim and desire to secure by Letters Patent is:

1. An earth moving implement including a frame, an upright rolling disc plow journaled in the frame and positioned to cut and direct earth laterally of the direc-

tion of travel, a rotor element supported by the frame for rotation about a generally upright axis, said rotor element comprising a substantially horizontally disposed disc-like hub having spaced about the periphery thereof a plurality of radially extending teeth, the outer ends of the teeth defining a circular path the leading portion of which path lies forwardly of the rearmost peripheral portion of the plow disc and adjacent the lowermost peripheral portion thereof, and drive means for rotating the rotor element at a speed substantially greater than the speed of rotation of the rolling disc plow whereby the teeth strike, carry and cast the earth flowing from the lower rear quadrant of the rolling disc laterally to one side of the direction of travel.

2. An earth moving implement as set forth in claim 1 including, means pivotally connected to the frame for supporting the disc plow for pivotal movement about an upright axis so the angle of the disc will be reversed commensurate with changed position relative to the axis.

3. An earth moving implement as set forth in claim 1 wherein the rotor element is mounted for substantially universal adjustment relative to the plow disc whereby said element and its members may be moved laterally, forwardly and rearwardly of said disc and lowered, raised and tilted relative thereto.

4. An earth moving implement as set forth in claim 3 including, supporting means pivotally connected to the frame for pivotal movement about an upright axis, the disc plow being suspended from the supporting means.

5. An earth moving implement as set forth in claim 1 including, an arcuate, substantially horizontal member mounted on the frame for supporting the plow disc rotor element, said disc being pivotally suspended from said frame for movement about an upright axis and said element having universal connection with the drive means whereby said disc and element may be swung from one side to the other and adjusted relative to said frame and to each other.

6. An earth moving implement as set forth in claim 5 including, means having connection with the rotor element and bearing against the frame member for raising and lowering said element and its members relative to the plow disc.

7. An earth moving implement including, a frame adapted to be pivotally mounted on a tractor for movement about a substantially horizontal axis, means for pivoting and holding the frame in adjusted positions, an upright rolling disc plow journaled in the frame and positioned to cut and direct earth laterally of the direction of travel, a rotor element supported by the frame for rotation about a generally upright axis, said rotor element comprising a substantially horizontally disposed disc-like hub having spaced about the periphery thereof a plurality of radially extending teeth, the outer ends of the teeth defining a circular path the leading portion of which path lies forwardly of the rearmost peripheral portion of the plow disc and adjacent the lowermost peripheral portion thereof, and drive means for rotating the rotor element at a speed substantially greater than the speed of rotation of the rolling disc whereby the teeth strike, carry and cast the earth flowing from the lower rear quadrant of the rolling disc laterally to one side of the direction of travel.

8. An earth moving implement as set forth in claim 7 wherein the plow disc is pivotally connected to the frame for pivotal movement about an upright axis, and means for holding said disc in adjusted positions.

9. An earth moving implement as set forth in claim 8 wherein the rotor element has universal connection with the drive means so as to be movable for adjustment relative to the plow disc, and means for holding said element in adjusted positions.

10. An earth moving implement as set forth in claim 9 wherein the frame includes an arcuate, substantially horizontal member at its rear portion for supporting the plow disc and rotor element in adjusted positions.

11. An earth moving element as set forth in claim 10 including, means having connection with the rotor element and bearing against the frame member for controlling the elevation of said element and its members relative to the plow disc.

12. An earth moving implement as set forth in claim 10 including, rotatable direction reversing means connecting the rotor element and drive means.

13. An earth moving implement as set forth in claim 7 including, a grader blade mounted on one end of the frame, the plow disc and rotor element being supported by the opposite end of said frame whereby the blade counterbalances said disc and element.

14. An earth moving implement as set forth in claim 7 wherein the frame extends longitudinally of the tractor and is pivotally mounted intermediate its ends adjacent the drive wheels of said tractor, the plow disc and rotor element being supported by one end portion of said frame, and a grader blade carried by the other end of said frame so as to counterbalance said disc and element, the weight of the composite implement increasing the traction of said tractor drive wheels.

15. An earth moving implement including a frame, an upright rolling concave disc plow journaled in the frame and positioned to cut and direct earth laterally of the direction of travel, a rotor element comprising a disc-like hub having spaced about the periphery thereof a plurality of radially extending teeth, said hub being mounted on a shaft journaled in the frame adjacent the disc plow, the outer ends of the teeth defining circular paths the leading portions of which lie forwardly of the rearmost peripheral portion of the plow disc and adjacent the lowermost peripheral portion thereof, and drive means for rotating the shaft and rotor element at a speed substantially greater than the speed of rotation of the rolling disc plow whereby the teeth strike, carry, and cast the earth flowing from the lower rear quadrant of the rolling disc laterally to one side of the direction of travel.

16. An earth moving implement as specified in claim 15 in which the rolling concave disc plow is journaled in an auxiliary frame, said auxiliary frame being attached to the main frame by means of a vertical pin or bolt making possible a reversal of the direction in which the earth loosened by the rolling disc is laterally directed, and means for holding the auxiliary frame in the reversed positions.
